BOTTLE

Brooks D. Fuerst, Toledo, Ohio, assignor to Owens-Illinois Glass Company, Toledo, Ohio, a corporation of Ohio

Filed Feb. 27, 1963, Ser. No. 73,743

Term of patent 14 years

(Cl. D58—8)

The characteristic feature of my design resides in the vertical grooves in the body portion which are wider at the top than at the bottom and which terminate short of the heel and terminate short of the tapering neck as shown.

I claim:

The ornamental design for a bottle, substantially as shown and described.
